UNITED STATES PATENT OFFICE.

MAXWELL C. MAXWELL AND CHARLES LEDIN, OF STAMFORD, CONNECTICUT, AS
SIGNORS TO THE YALE & TOWNE MANUFACTURING COMPANY, OF STAMFORD, CON-
NECTICUT.

LOCK.

Application filed August 14, 1923. Serial No. 657,275.

To all whom it may concern:

Be it known that we, MAXWELL C. MAXWELL and CHARLES LEDIN, citizens of the United States, and residents of Stamford, 5 in the county of Fairfield and State of Connecticut, have invented certain new and useful Improvements in Locks; and we do hereby declare the following to be a full, clear, and exact description of the invention, such as will enable others skilled in the art to which it appertains to make and use the same.

This invention relates to improvements in locks,—one object of the invention being to 15 provide means whereby the operation of the bolt-operating cam will be blocked, or prevented from effectual operation by the insertion of a tool, in the event attempt be made to pull or twist the cylinder of the 20 lock from its connection with the back plate of a rim lock and the door so that access might be had to the roll-back for operating the same to withdraw the bolt with the use of a tool.

25 A further object is to so construct the back cover-plate of a rim lock that it will become distorted in the event that attempt be made to pull or twist the cylinder of the lock from its position and prevent the effectual throw of the roll-back cam.

With these and other objects in view, the invention consists in certain novel features of construction and combinations of parts as hereinafter set forth and pointed out in 35 the claims.

In the accompanying drawings:—

Figure 1 is a face view of a back cover-plate for a rim lock and showing an application of our improvements.

40 Figure 2 is a sectional view on the line 2—2 of Figure 1.

Figure 3 is a sectional view (with the roll-back in elevation) on the line 3—3 of Figure 1.

45 Figure 4 is a face view of a back-plate showing a slight modification.

Figure 5 is a sectional view, on the line 5—5 of Figure 4.

50 Figure 6 is a sectional view, partly in elevation, on the line 6—6 of Figure 4, and

Figures 7 and 8 are views showing another form of construction.

A sheet metal back or cover plate for a rim lock is shown at 1 and is provided with 55 suitable holes 2 for the accommodation of

fastening means which secure the cover plate to a lock casing.

At approximately the center of the plate 1, a suitable opening is provided for the accommodation of a roll-back 3 having a 60 roll-back cam or bolt operating member 4 connected therewith as is usual in types of lock such as those to which our improvements relate. The plate 1 is provided in proximity to the mounting of the roll-back cam with holes 5 for the accommodation of bolts (not shown) which secure a lock cylinder in place. Four such holes are shown and either the upper or the lower pair of holes may be utilized for the accommodation 65 of such securing bolts.

The cover plate 1 is weakened in such manner that in the event attempt be made to pull or twist the lock cylinder from the door, a portion of said plate will be so distorted as to change the angle of the mounting of the roll-back to such an extent that the roll-back cam will be caused to engage the face of the plate and be prevented thereby from being moved sufficiently to 75 withdraw the bolt of the lock,—the plate itself thus acting as blocking means for the roll-back cam. The plate 1 may be weakened for the purpose above stated by providing approximately T-shaped slots 6 near 80 respective sides or above and below the mounting of the roll-back cam as indicated in Figure 1. Instead of making T-shaped slots as above described in the plate 1, said plate may be provided with diametrically 85 opposite, approximately semi-circular slots 7, as illustrated in Figure 4.

The plate 1 may be weakened in the manner shown in Figures 7 and 8 for the purpose hereinbefore explained, by slotting or 95 slitting said plate in a manner to provide tongues 8 at respective sides of that portion of the plate to which the cylinder of the lock is to be secured. This may be accomplished by shearing down the metal of the plate in the form of the tongues 8 and then bending back the metal to its former position level with the surrounding surface.

Having fully described our invention what we claim as new and desire to secure by 105 Letters Patent, is:—

1. In a lock, the combination of a back or cover plate provided with a normally rigid part adapted for the reception of cylinder lock fastening means, a bolt operat- 110

ing member carried by said part, said part being displaceable relatively to the body of the plate by the application of force to a cylinder lock when secured thereto, to render the bolt operating member inoperable.

2. In a lock, the combination of a back or cover plate having a distortable portion adapted for the reception of securing means for a cylinder lock, and a bolt operating means carried by the distortable portion of said cover plate.

3. In a lock, the combination of a back or cover plate adapted to have a cylinder lock secured thereto, a bolt operating cam carried by said plate, and means whereby that portion of the cover plate to which the cylinder lock may be secured will be distorted if said cylinder lock be forcibly pulled or twisted and thus prevent the effective throw of the bolt operating cam.

4. In a lock, a back or cover plate adapted to have a lock cylinder secured thereto, said cover plate being weakened adjacent to that part to which the lock cylinder is to be secured, whereby said portion may become distorted by the application of force.

5. In a lock, a back or cover plate adapted to have a cylinder lock secured thereto, said cover plate being cut in proximity to that portion of the plate to which the lock cylinder is to be secured, whereby said portion of the plate will be subject to distortion upon the application of force.

6. In a lock, the combination of a back or cover plate, a roll-back cam mounted therein, said cover plate having slots at respective sides of the mounting of the roll-back cam and also having holes in the area between said slots for the reception of fastening means for a cylinder lock, whereby that portion of the plate which receives the cylinder fastening means may be distorted.

In testimony whereof, we have signed this specification in the presence of two subscribing witnesses.

MAXWELL C. MAXWELL.
CHARLES LEDIN.
